SHIPPING CRATE

Filed June 4, 1931

FIG. 3.

FIG. 4.

FIG. 5

By

J. H. Grande,
C. Williamson
Attorney

UNITED STATES PATENT OFFICE

JOSEPH H. GRANDE, OF ALHAMBRA, CALIFORNIA

SHIPPING CRATE

Application filed June 4, 1931. Serial No. 542,142.

The object of my invention is to enable the shipment of fresh vegetables over long routes without injury or deterioration from their presence in temperatures that otherwise would be hurtful and to accomplish this important object by packing means of simplicity and low cost. My invention is embodied in a refrigerator crate in which the fresh vegetables are placed in superimposed horizontal layers or tiers.

An important feature of my invention is the provision of a refrigerant holder or receptacle (such a refrigerant as dry ice) which will not diminish the vegetable storage space within the crate, nor add to the external dimensions of the crate, my invention in this particular utilizing crate space that is wasted. The standard or conventional crate made of spaced apart parallel wood slats or strips has at each end a necessarily stout rectangular frame of wood which on the inner side has a crate end wall so that within the frame and on the exterior of the crate is a frame-enclosed space of considerable volume or capacity. I make use of that space at each end of the crate by placing therein a box of wood or other suitable material, the box walls or sides being affixed or secured to the bars which form the end frame. Thus not only is the otherwise unused space utilized, but the means for utilizing it add to the strength of the crate structure at the ends and at trifling cost.

Another feature of my invention is the use in connection with vegetables, such as lettuce, that are apt to become discolored, of a preserving and bleaching solutions, such as a preparation known as citric acid crystal solution. The butt ends of the heads of lettuce are apt to become discolored in transit and that is prevented by dipping such ends in said solution.

I illustrate in the drawing an embodiment of my invention in a conventional or standard wood crate, because, in such embodiment, all of the features of my invention are very advantageously utilized, but I do not restrict myself to that particular embodiment.

My invention consists in whatever is de-

scribed by or is included within the terms or scope of the appended claims.

In the drawing:—

Fig. 1 is a perspective view of a shipping crate embodying my invention;

55

Fig. 2 is a longitudinal section thereof;

Fig. 3 is a cross-section on the line 3—3 of Fig. 2;

55

Fig. 4 is a top plan view showing the procedure in applying the cardboard wall linings that are interposed between the food articles packed in layers within the crate;

60

Fig. 5 is a plan view of a portion of one of the partition or separator sheets preferably used.

65

Describing in detail what is shown in the drawing, the shipping box or crate is of six flat sided form whose length is greater than its other dimensions, as in the standard or ordinary construction, and includes two similar rectangular end frames, 10, of bars or strips of wood nailed or otherwise secured together and slats or strips, 11, of thin wood extending between the end frames and nailed at their ends to the outer sides of said end frames, on all four sides thereof when the crate or box is packed and ready for shipment or other handling.

70

All of the inner sides of the crate body are covered or lined with liquid-proof sheets of cardboard so that the vegetables or other food commodities packed within the crate are completely enclosed by these sheets. Said sheets,

75

12, are of such form and number that by folding on lines parallel with the edges or corners of the crate they cover the entire inner surfaces of the crate and enclose the contents on all sides. What are the top portions of the sheet during the placing and packing of the vegetables, or other food articles therein, are carried over the top edges of the crate walls or sides and are projected outside thereof, and afterwards when the crate is packed, such top flaps are folded back over the topmost layer of vegetables or food articles with one flap lying upon another when all are folded over, and thereafter the slats for that side of the crate are nailed to the end frames.

80

Within the lined walls of the crate, food

85

90

95

100

articles or commodities, such for example, heads of lettuce L, are packed in parallel layers one above another and between adjacent layers is placed a separating or partition sheet, 13, of cardboard or heavy paper that extends entirely across the space between the side walls of the crate. The separator sheets are perforated and preferably perforated by numerous V-shape slits, 14, as best shown in

10 Fig. 5.

By the separator sheets each layer of commodities is separated from an adjacent layer and spaces between adjacent layers are assured for the flow or circulation or dissemination 15 of the refrigerant or cooling medium stored or placed within the crate, and by the perforations in the separators, the circulation is assured between the layers so that all of the articles within the crate are adequately 20 and efficiently acted upon by the refrigerant or refrigerating medium, or the refrigerant emanations therefrom, with the result that even after long shipments the crate contents are preserved in a fresh, wholesome and attractive-looking state.

Preferably the separator sheets are of or contain a material which makes them heat insulators. This prevents the rapid dissipation of the refrigerant and enables them to retain 30 their stiff flat form against the disintegrating effect of moisture absorption. With the openings 14, in the form of slits, there is effected a certain control of moisture tending to pass through the perforations because 35 the slit edges will swell from the action of moisture thereon and tend to close up the slits and thus the advantageous effect of moisture on the vegetables will be utilized. The cutting of the fibers in forming the slits facilitates 40 absorption of moisture by the slit edges and in a way effects water storage in the partitions in contact with vegetables. The advantages with regard to the action or effect of moisture are particularly pronounced 45 when the refrigerant used is ice because of the quantity or volume of water which is produced by melting of the ice.

As I have already explained, there is a refrigerant-holding compartment or chamber 50 at each end of the crate. Each such compartment or chamber comprises an outer solid wall or panel 15 of wood which extends across the space between opposite end frame bars and overlaps the latter at its ends and is 55 nailed thereto and an inner wall, 16, also of wood which likewise extends between said end frame bars and overlaps them on their inner sides and is nailed thereto. Thus opposite bars of the end frame constitute opposite 60 sides of the chamber. The remaining narrow sides of the chamber in the space within the end frame are formed by two bars of wood, 17, that extend between and at their end abut against the inner sides of the end frame bars to which the outer and inner walls

15 and 16 are nailed, and, of course, they fill the space between said outer and inner walls 15 and 16. It will be seen that the chamber with walls, formed as described, by reason of the connection of the walls with the end frame bars materially adds to the strength 70 of the crate at the ends and with but little addition to the weight thereof and at trifling cost.

The inner chamber walls 16, are provided 75 with numerous holes or perforations 18, but all other walls of the chamber are solid or imperforate, the result being that circulation or flow of the refrigerant or refrigerating medium is wholly to the interior of the crate and at the ends of the separated layers of vegetables, or other food commodities packed in the crate, and on all other sides the chamber is insulated so that the refrigerant therein is safeguarded from the melting effect of the surrounding temperature. These chambers are admirably suited for the use of dry ice, I, that is, solid carbon-dioxide. As it 80 "melts" or passes into the gaseous state, which is in large volume, it flows under the pressure 85 produced from the opposite chambers into and through the packed lettuce or other food commodities within the crate, holes, 19, being provided in the adjacent liner sheet.

Safeguarded and kept fresh by the refrigerant and protected from discoloration by the bleaching and preservative solution applied to those parts of the vegetables requiring that treatment, crates of vegetables or like food commodities packed in crates embodying my 100 invention will reach remote destinations from the point of shipment in a fresh, wholesome and attractive-looking condition.

Of course, in some embodiments of my invention other material than wood may be 105 used to form the crate body.

What I claim is:—

1. A refrigerator shipping crate having 110 external walls, partitions extending substantially parallel between such walls and spaced apart by layers of food commodities and an end refrigerant chamber wholly external to the storage space within the wall.

2. A refrigerator shipping crate having 115 external walls, partitions extending substantially parallel between such walls and spaced apart by layers of food commodities and an end refrigerant chamber wholly external to the storage space within the wall, said walls being of heat insulating sheet material with- 120 in an external crate body.

3. A refrigerator shipping crate having 125 external walls, partitions extending substantially parallel between such walls and spaced apart by layers of food commodities and an end refrigerant chamber wholly external to the storage space within the wall, said walls being of heat insulating sheet material with- 130 in an external crate body, said crate body

having opposite end frames and said chamber being situated within an end frame.

4. A refrigerator shipping crate having external walls, partitions extending substantially parallel between such walls and spaced apart by layers of food commodities and an end refrigerant chamber wholly external to the storage space within the wall, said walls being of heat insulating sheet material with-
10 in an external crate body, said crate bcdy having opposite end frames and said chamber being situated within an end frame, certain of the chamber walls being opposite bars of said end frame.
15 5. A refrigerator shipping crate body with slat connected end frames and a refrigerant chamber within an end frame with outer and inner walls extending between opposite bars of said end frame and overlapping said bars,
20 said end frame bars constituting opposite walls of said chamber and remaining walls of said chamber consisting of bars lying between said outer and inner walls and extending between the frame bars to which said
25 outer and inner walls are attached.

6. A refrigerator shipping crate having external walls enclosing a storage space and separator partitions spaced apart and extending between said walls with a layer of
30 food commodities between adjacent partitions, such partitions having perforations and means to supply a refrigerating medium to the spaces between such partitions.

7. A vegetable refrigerator shipping crate
35 of a form with six flat sides having external walls enclosing a vegetable receiving space closed thereby to the outside such face being continuous from top to bottom, side to side and end to end of the crate, means within
40 such space supporting vegetables in layers and refrigerant holding means from which there is circulation through the layers of vegetables of a low temperature medium.

In testimony whereof I hereunto affix my
45 signature.

JOSEPH H. GRANDE.
